UNITED STATES PATENT OFFICE.

JOSEPH K. SHARPE, JR., OF INDIANAPOLIS, INDIANA, ASSIGNOR TO THE SCHUMAN COMPANY, OF INDIANAPOLIS, INDIANA, A CORPORATION OF MAINE.

SHOCK RECEIVING AND DELIVERING MEANS FOR SHREDDING-MACHINES.

1,074,653.

Specification of Letters Patent.

Patented Oct. 7, 1913.

Application filed February 23, 1911. Serial No. 610,122.

To all whom it may concern:

Be it known that I, JOSEPH K. SHARPE, Jr., a citizen of the United States, residing at Indianapolis, in the county of Marion and 5 State of Indiana, have invented certain new and useful Improvements in Shock Receiving and Delivering Means for Shredding-Machines, of which the following is a specification.

10 The object of my invention is to provide a simple and efficient device for elevating shocks of corn upon a shredder and delivering the same adjacent the shredding and husking mechanisms of such machines within 15 convenient reach of the operator so that such material may be in position to be constantly supplied to said mechanisms while at the same time a further supply is being continually elevated to be placed in feeding position, 20 as will be hereinafter more particularly pointed out.

In the accompanying drawings, which form a part hereof, Figure 1 is a plan of a portion of a shredder with my improvements applied thereto; Fig. 2 a front elevation; Fig. 3 a longitudinal section on the dotted line 3—3 in Fig. 1; Fig. 4, a perspective of the mast-supporting spider which I employ; Fig. 5 a perspective of my improved rotary feeding table; and Fig. 6 is a detail showing the means for locking said table in its various positions.

In said drawings the portions marked 10 represent the shredder, 11 the husking and 35 snapping rolls, and 13, 14, 15, walls constituting the feeding hopper.

Near the forward end of the shredder I mount a spider, 17, upon suitable supporting members, as 18, or otherwise, to which 40 spider a track, 19, is secured in any desired manner, or where desired said spider and track may be formed integrally. Centrally of said spider 17, as at 20, I mount the base member, 21, of a mast, 22, having a cross-member, 23, or other suitable means at its upper end for supporting pulleys, 24. Said mast 21 extends through and constitutes an axial bearing for my improved rotary feeding table, 25, which I preferably provide 50 with a sleeve, 26, by which it may be securely mounted on said mast. Said table 25 I prefer to seat within a surrounding platform, 27, and provide the same with divisional walls, 30, 31, 32, which form compartments, 55 33, 34, 35, each for the reception of a corn

shock and for supporting the same in upright position. The under side of said rotary table is provided with rollers, 36, or other suitable anti-friction devices for rotatively supporting said table on the track 60 19. Adjacent said mast, or at any appropriate point, I mount suitable winding mechanism for operating the shock-elevating cables, 40, 41, which preferably pass over the pulleys 24 and down through said 65 mast and are attached to said winding mechanism, which latter may comprise a shaft, 42, supported by bearings, 43, and upon which shaft I mount winding drums, 44, 45, one for each cable, and which drums are provided on their adjacent ends with clutch members, 46, 47, adapted to be engaged by a clutch member, 48, mounted on said shaft, the latter being also provided with a driving pulley, 49, adapted to be belted to any desired power pulley on the shredder by longitudinally shifting shaft 42, which is held in adjustable position by collars, 50, by which means pulley 49 may be readily brought into alinement with a shredder pulley. Any suitable mechanisms may be employed for automatically throwing clutch member 48 into or out of engagement with either of said drums 44, 45, as, for example, those shown in Patent No. 893,387, and as 80 said winding mechanism illustrated forms no part of my present invention it will not be further described herein, as I may select appropriate or well known winding mechanism for operating said shock elevating cables 40, 41.

In order to facilitate the elevation of the shocks from the ground I provide guides or runways, as 55, at either side of platform 27, which may be hooked or otherwise secured thereto, and up which a shock may be guided while being elevated to the rotary feeding table 25. Each of said shock compartments may at all times be held in positive receiving and feeding position by means 95 of an automatic catch, as 56, communicating with platform 27 and table 25, as indicated in Fig. 6.

In the drawings I have shown a feeding table comprising three shock-receiving compartments, but it will be understood that any desired number may be employed. In operation, the end of a cable, as 40, is drawn out to and secured to a shock, when the cable-winding mechanism is set in motion to 105 110

wind up said cable, which latter draws the shock to and up the inclined guide 55 and across platform 27, and continues its upward movement until the shock is suspended over a compartment, as 33, Fig. 1, when said cable is released and the shock deposited into said compartment. The cable is then removed, and the table, by releasing the automatic catch 56 by foot pressure or otherwise, may be rotated manually or otherwise until compartment 33, with its shock, is brought into registry with the feeding hopper of the machine, and occupies the position of compartment 34, Fig. 1, when the shocked material to be fed to the husking rolls is thus within convenient reach of the operator, who stands on platform 27 near the feeding hopper. While such material is being removed from compartment 33 other shocks in like manner are being delivered from opposite sides of the machine into compartments 34 and 35, which in turn are brought by rotation into feeding position. In cases where it is desired to use but two of the compartments, as for instance 34 and 33, compartment 34, when freed from material and unlocked, may be shifted to the position shown to be occupied by compartment 35, at which operation compartment 33 with its shock is brought to feeding position, and when freed from material (in the meantime compartment 34 having been loaded) may be shifted back to original position, during which movement compartment 34 with its shock is brought to feeding position, so that these two compartments may be utilized alternately to deliver shocks from each side of the machine by simply shifting them back and forth, thus obviating the necessity of completely rotating the feeding table in one direction each time a shock is brought to feeding position.

I claim as my invention.

1. Shock receiving and delivering mechanism for shredding machines, comprising a mast, a rotary table associated with said mast and having divisional walls constituting shock receptacles, an elevating cable supported by said mast, and winding mechanism communicating with said cable for actuating the same to elevate shocks upon said table.

2. Shock receiving and delivering mechanism for shredding machines, comprising a track, a table mounted on said track and having divisional walls constituting shock receptacles, a mast projecting through said table, a cable carried by said mast, and winding mechanism communicating with said cable for operating the same.

3. Shock receiving and delivering mech-

anism for shredding machines, comprising a table having a base and divisional walls, and means for movably supporting said table to shift shocks from receiving to delivering positions.

4. Shock receiving and delivering mechanism for shredding machines, comprising a table having a base and divisional walls, a track, anti-friction bearings between said base and track, and means for holding said table in predetermined position.

5. Shock receiving and delivering means for shredding machines, comprising a track, a table mounted on said track and having divisional walls constituting shock receptacles, a mast constituting an axial bearing for said table, means associated with said mast for encircling and elevating a shock, and means for actuating said shock-elevating means.

6. Shock receiving and delivering means for shredding machines, comprising a mast, a table rotatably mounted thereon and having divisional walls constituting shock receptacles, a cable supported by said mast one end of which is adapted to encircle a shock, and means for drawing said cable above said table to deposit a shock thereon.

7. Shock receiving and delivering means for shredding machines, comprising a support, a table rotatably mounted thereon and having divisional walls constituting shock receptacles, means associated with said table for elevating shocks thereon, and means for actuating said shock elevating means.

8. Shock receiving and delivering means for shredding machines, comprising a movable table having compartments one of which registers with the feeding hopper of said machine and another of which is positioned to receive material elevated at one side of said machine, means for securing said table in position, means associated with said table for elevating shocks thereon, and means for actuating said shock elevating means.

9. Shock receiving and delivering means for shredding machines, comprising a rotary table having compartments each adapted to receive material and deliver the same in proximity to the husking mechanism of said machine, means associated with said table for elevating shocks thereon, and means for actuating said shock elevating means.

In testimony whereof I affix my signature in presence of two witnesses.

JOSEPH K. SHARPE, JR.
